UNITED STATES PATENT OFFICE.

WILLIAM ELY, OF PROVIDENCE, RHODE ISLAND.

ELECTRIC SWITCH.

SPECIFICATION forming part of Letters Patent No. 634,057, dated October 3, 1899.

Application filed February 4, 1898. Renewed February 27, 1899. Serial No. 707,092. (No model.)

To all whom it may concern:

Be it known that I, WILLIAM ELY, a citizen of the United States, residing in the city and county of Providence, in the State of Rhode Island, have invented a new and useful Electric Switch, of which the following is a specification.

In many forms of electric switches heretofore known it has proven possible at the will of the operator to retard or suspend the movement of the connecting parts during the operation of making and breaking the circuit, and in other forms it has proven possible to similarly retard or suspend the movement of the connecting parts during the operation of breaking the circuit. The effect of such retardation or suspension of the movement of the connecting parts of the switch is to prevent the requisite sudden connection or separation of the connecting parts and the contact-sections of the switch, thereby causing an uneven distribution of the current, rendering the parts of the switch liable to be fused or burned out, and increasing the danger not only of fire, but also to life.

The purpose of my invention is to provide an electric switch in which the action of the switch mechanism shall be positive, sudden, and automatic both in making and in breaking the circuit and when once initiated shall be beyond the control of the operator and in which the primary actuating means shall be isolated from the current-carrying parts of the switch.

My invention consists in the novel construction and arrangement of the mechanism hereinafter described, and shown in the accompanying drawings, in which—

Figure 1 is a top plan of my switch as applied in connection with contact-plates. Fig. 2 is a vertical section on line 2-2 of Fig. 1. Fig. 3 is a horizontal section on line 3-3 of Fig. 2. Fig. 4 is a side elevation of my switch as applied to a "knife-switch."

Similar reference letters and numerals indicate like parts where they occur in the drawings.

Upon the base A, constructed in the usual way of insulating material, are secured, preferably in line with each other, the rotatable shaft 4, mounted in said base and extending in both directions beyond the same, and a sta-

tionary post or stud 5, likewise projecting beyond the faces of said base. Upon one end of said shaft I secure an arm 6, and upon the corresponding end of the post 5 I secure another arm 7 and pivotally connect the ends of said two arms by the insulating-links 8 and 9. Said arms are provided with extensions at each end, by which the contact is effected with the contact-posts 10, 11, 12, and 13, secured to said base in the usual manner. Upon the opposite end of said rotatable shaft 4 I rigidly secure a second arm 14, and also loosely pivot an arm 15, provided with a geared portion 16 and projecting lugs, ears, or thickened portion 17, adapted to engage with said arm 14 to actuate the shaft 4. Upon the opposite end of the post or stud 5 is pivoted an actuating lever or handle 20 and also a segment-gear 21, arranged to releasably mesh with the geared portion of the arm 15. Said arm 15 and gear 21 are connected by means of the extensible spring 22. Said segment-gear 21 is provided with thickened portions 75 or lugs 23, adapted to be engaged by said lever or handle 20 to rotate said gear.

The operation of my invention is as follows: Referring to Fig. 1, in which the switch is represented as closed—i.e., the circuit made—80 it will be observed that the gear 21 is out of mesh with the geared portion of the arm 15, while the lever 20 rests at one side of the switch-box B. If the lever 20 be now forced over toward the opposite side of the box, it 85 will rotate the gear 21 and cause it to mesh with the part 16 of the arm 15. Continuing, the movement of the lever 20 will cause the arm 15 to rotate and distend the spring 22 until it reaches the dead-center line. Up to 90 this point the arms 6 and 7 and their connections have not started and the current is uninterrupted; but the spring 22 is under its extreme tension. A slight further movement of the lever 20 carries the spring by its dead-center line, and it at once reacts to throw the arm 15 with force against the arm 14 and out of mesh with the gear 21. The first effect of the described action is to cause the arm 15 to strike the arm 14 a powerful blow, and thereby give an initial positive movement to the arms 6 and 7 to overcome the frictional and other resistance between them and the contact-posts. The second is to cause an instant-

stantaneous increase of the speed of the movement initiated as described, completing the movement, and breaking with the requisite suddenness the connection between said arms 5 and contact-points, and throwing and holding the gear and arm 15 out of mesh with each other, thereby isolating the gear and the handle 20 from the current-carrying parts of the switch. To make the circuit, the described 10 movements are reversed.

The handle or lever 20 and the gear 21 are, as shown, pivoted independently of each other, and the gear will, under the influence of the spring 22, have a certain amount of 15 movement without reference to the movement of the lever, thus insuring its complete isolation from the current-carrying parts of the switch while the latter are in either their open or closed position, and also removing 20 said parts absolutely from the control of the lever when once the spring has begun to operate to actuate them either to open or close the circuit.

I claim as my invention and desire to secure by Letters Patent—

In an electric switch the combination of the contact-posts and the contact members, the gear-segment lever loosely connected with the

contact members, the engaging arm in positive connection with the contact members and 30 adapted to permit the required backlash movement between the gear-segment lever and the engaging arm, the hand-operated lever, the actuating gear-segment lever loosely connected with said hand-operated lever with 35 the required degree of backlash, and the spring connecting the ends of the gear-segment levers whereby upon the initial movement of the hand-operated lever the teeth of the gear-segment levers will be brought into 40 engagement and the spring will be distended without causing the movement of the contact members, until at the passage of said spring beyond the dead-center line the action of said spring will cause the required sudden movement of the contact members and the disengagement of the teeth of the gear-segment levers, substantially as described.

In testimony whereof I have hereunto set my hand, in presence of two witnesses, this 50 2d day of February, one thousand eight hundred and ninety-eight, (1898.)

WILLIAM ELY.
